UNITED STATES PATENT OFFICE.

RICHARD C. JORDAN, OF OTTAWA, ILLINOIS.

HAY-CARRIER.

SPECIFICATION forming part of Letters Patent No. 320,876, dated June 23, 1885.

Application filed October 30, 1884. (No model.)

To all whom it may concern:

Be it known that I, RICHARD C. JORDAN, a citizen of the United States, residing at Ottawa, in the county of La Salle and State of Illinois, have invented certain new and useful Improvements in Hay-Carriers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figures 1, 2, and 3 are side views showing my device in different positions. Figs. 4 and 5 are perspective detail views.

This invention relates to improvements in hay-carriers; and it consists in the construction and novel arrangement of devices as hereinafter fully described, and pointed out in the appended claims.

Reference being had to the accompanying drawings and the letters of reference marked thereon, A represents the carrier-frame, of the usual general shape, composed of the two similar parallel plates a a, and provided at its upper corners with the wheels a' a', which travel in the usual manner upon the beam or the iron or cable track B, as shown.

a' is a vertical funnel-shaped tube or passage situated centrally between and fixed to the plates a, and converging from below upward. The said passage is cut away on its front and rear aspects to give room for the play of the latching mechanism.

C is a ring fixed to one of the lower corners of the carrier-frame, centrally between the plates a, and D is a pulley, the shaft of which has bearings in said plates at the opposite corners of the frame.

E is a crescent-shaped locking-hook, pivoted at e between the plates a, on the same side of the passage as the pulley D. e' is the lower inwardly-pointing locking-point of said hook, and e² is the upper point of the same, against which the ascending loop strikes to rotate the hook, as hereinafter described. e³ e⁴ are similar shoulders formed on the face of the hook on each side of the point e², and e⁴ is a point curving outward and somewhat down-

ward from the back of the hook when the same is locked.

F is a detent-bar for holding the carrier at the desired position on the beam B. The said bar is pivoted at f between the plates a, above the locking-hook and on the same side of the carrier as the ring C, its inner arm being heavier than its outer arm, f'. f² is a vertical longitudinal slot in the said bar, extending into the outer arm and having the pivot of the bar passing through it. f³ is the hook-shaped end of the outer arm of the bar F, having its upper edge beveled downward and outward, and f⁴ is the curved end on the inner arm, with its concavity downward. f⁵ is a guide point or plate projecting downward from the lower surface of the inner arm of the bar, just to the rear of its curved end.

G is a detent-bar bolted to the under surface of the beam A, and provided with a downwardly-projecting arm, g, which inclines away from the carrier, and has its point beveled in the same direction.

H is the locking-bar of the device passing through the slot f² of the detent-bar, and turning on the same pivot therewith, its inner arm being heavier than its outer arm. The outer arm of said locking-bar is widened, and has its end h beveled from above, downward and outward, so that when it strikes against the arm g it will turn on its point, and the inner arm will be raised. The end h' of the inner arm of the bar is hook-shaped, with its concavity downward, and is slotted vertically and longitudinally at h², for a purpose hereinafter explained. The slot h² extends past the hooked end into the arm of the bar H, and the guide point or plate f⁵ passes and moves in said extension. h³ h⁴ are shoulders formed on the inner arm to engage with the shoulders e³ e⁴ on the locking-hook.

I is a block provided on its upper edge with a vertical loop or hook, i, and having the pulley or sheave i' turning in it in the usual manner. i² is a hook fixed to the lower edge of the back and curled and bent over on itself, with its point long, so as to prevent the hay-fork or load connected therewith from being easily detached.

J is the actuating-rope of the device, having its end secured to the ring C, thence passing

under the pulley i , and over the pulley D, as shown.

The detent-bar G is so placed on the beam A that the carrier will stand, when locked, 5 over the load of the hay to be moved.

The operation of the device is as follows: It being supposed that the carrier is returning to take a fresh load, the beveled edge of the hook f^3 will first strike the arm g , slide under the same, and lock thereon. The carrier still advancing, the end h of the locking-bar will strike the arm g , throwing up the inner arm of the locking-bar H and releasing the shoulders h^3 from the shoulders e^3 . The locking-hook E then rotates, releasing the loop i from the point e , swinging the hook e^4 out of the slot h^2 , and allowing the block I, with connected hay-fork, to descend, supported by the rope J. The carrier is now held in one place (over the load) on the beam A, but the lifting devices are unlocked from the carrier. A load of hay is now secured to the fork, and the rope J is drawn upon, causing the lifting devices to rise. The loop i strikes the point e^2 , lifting it, causing the hook E to rotate and the point e^2 to engage the loop. The loop is still continuing to rise. The shoulders h^3 are drawn behind the shoulders e^3 as the latter turn, the hook e^4 having passed into the slot in the hooked end h of the locking-bar H, and by its pressure therein causing the result. The further upward movement of the loop i causes the point e^2 to rotate under the guide-point f^5 of the inner arm of the detent-bar F, raising the same and detaching the hook f^3 from the detent-arm g .

Having thus described my invention, what I desire to secure by Letters Patent is—

1. In a hay-carrier, the combination, with the pivoted locking-hook E, provided with the shoulders e^3 and the hook e^4 , and arranged to be rotated by the loop i of the locking-bar H, provided with the slot h^2 and shoulders h^3 , and arranged to be lifted by the detent G, substantially as specified.

2. In a hay-carrier, the combination, with a carrier-frame having a swinging locking-hook pivoted thereto, and a detent-bar fixed to the beam on which the carrier travels, of a detent-bar and a locking-bar, each pivoted to the 50 carrier-frame, and so arranged that the swing of the locking hook will cause it to engage the locking-bar before said hook releases the detent-bar from the detent, substantially as specified.

3. In a hay-carrier, the combination, with the carrier-frame having a swinging locking-hook pivoted thereto, and a detent-bar fixed to the beam on which the carrier travels, of a detent-bar and a locking-bar, each pivoted to 60 the carrier-frame, and so arranged that the detent will engage the detent-bar before said detent releases the locking-bar from the locking-hook, substantially as specified.

4. In a hay-carrier, the combination, with 65 the beam B and detent G, of the carrier-frame provided with supporting-rollers, the detent-bar F, constructed as described, and provided with the guide-point f^5 at the curved portion thereof, the locking-hook E, funnel-shaped 70 tube a^2 , block I, provided with the loop i , and operating-rope J, substantially as specified.

5. In a hay-carrier, the combination, with the beam B, detent G, and carrier-frame A, of the detent-bar F, constructed as shown, the 75 locking-bar H, having one end hook-shaped and slotted longitudinally, and the opposite end beveled outward and downwardly, the locking-hook E, block I, provided with the loop i and pulley i' , and the rope fixed to the 80 ring C, and passing under the pulley i' and over the pulley D, substantially as specified.

In testimony whereof I affix my signature in presence of two witnesses.

RICHARD C. JORDAN.
